(57) **CLAIM**

The ornamental design for a "microphone," as shown and described.

DESCRIPTION

FIG. 1 is a perspective view of a microphone in accordance with my design;

FIG. 2 is a top plan view thereof;

FIG. 3 is a bottom plan view of thereof;

FIG. 4 is a front elevational view thereof; the rear elevational view being the mirror image of FIG. 4; and,

FIG. 5 is a right elevational view of thereof, the left side elevational view being the mirror image of FIG. 5.

The broken line portion of the figure drawings is included to show unclaimed subject matter only and forms no part of the claimed design.
